AIR CLEANER

William A. Shaw, Denver, Colo.

Application November 23, 1937, Serial No. 176,096

4 Claims. (Cl. 183—81)

This invention relates to air cleaners for carbureters and particularly to cleaners designed for removing dust and other foreign matter from the air entering a carburetor, and the general object 5 of the invention is to provide a very simple and improved device for this purpose, which is so constructed as to prevent dust-laden air from being agitated at the point where the air leaves the cleaner to pass into the carburetor.

10 Another object is to provide a structure of this character having a screen so disposed that splashing mud or driving rain will not strike the intake of the cleaner and foul it, and a further object in this connection is to provide a cleaner of this 15 character with a receiving chamber having a screened air inlet opening on its underface so that this opening is protected from being clogged by foreign matter or by mud.

A still further object is to provide a structure 20 of this character which embodies a receiving chamber, an air circulating chamber or "cyclone" in which the air entering the cleaner is whirled around a central pipe which in turn is connected to the carburetor, this central pipe being so 25 formed as to prevent the air as it leaves the spiral of the "cyclone" chamber, from agitating the air which is entering the mouth of the pipe leading to the carburetor to thus prevent dust from entering the carburetor but permit this dust to pass 30 downward by gravity and eventually be discharged into a receptacle.

Other objects will appear in the course of the following description.

My invention is illustrated in the accompanying drawing wherein:

Fig. 1 is a side elevation of an air cleaner constructed in accordance with my invention;

Fig. 2 is a top plan view of the structure shown in Fig. 1;

Fig. 3 is a fragmentary elevation of the central pipe;

Fig. 4 is a side elevation of this pipe;

Fig. 5 is a perspective view of the inner cone;

Fig. 6 is a section on the line 6—6 of Fig. 1;

Fig. 7 is a fragmentary section on the line 7—7 of Fig. 6;

Fig. 8 is a fragmentary vertical section through the external and internal cones and the dust receptacle;

Fig. 9 is a fragmentary vertical section of a modified construction of the external and internal cones.

Referring to the drawing, 10 designates a casing having a screen 11 on its underface. This 55 casing has a side wall 12 and an end wall 13. The

side wall 12 is curved and merges into the peripheral wall 14 of a cyclone chamber 15, which extends downward from the wall 12. Centrally disposed within the chamber 15 is an air outlet pipe 16 which at its upper end opens into a passageway 17, which in turn, as clearly shown in Fig. 7, opens into the vertical pipe 18 and extends down to the air intake of the carburetor. The pipe 16, as shown best in Figs. 3 and 4, is formed at its lower end with a laterally disposed 10 downwardly extending lip 19 constituting a shield. Extending around the central pipe 16 in a spiral course is a spiral partition 20. This extends through nearly a complete turn and discharges at the lower end of the chamber 15 and at a point 15 behind the lip or extension 19.

Extending downward from the peripheral wall 14 of the chamber 15 is a cone 21 having a small opening 22 in its lower end. Attached to the cone 21 and extending downward therefrom is an annular support 23 which supports a receptacle 24 at the lower end of the cone, this receptacle being for the purpose of gathering the dust. Disposed within the cone 21 is an inner cone 25, which tapers upwardly and has its apex disposed above 25 the lower end of the lip 19 but below the plane of the greater portion of the lower end of pipe 16. This cone 25 is supported on the cone 21 in spaced relation thereto by a plurality of supports 26 so that a slight space is left between the periphery of the internal cone 25 and the wall of the external cone 21 for the passage of dust into 30 the lower end of the cone 21.

While this is the preferable manner of disposing the internal cone, yet I do not wish to be 35 limited to this, and in Fig. 9, I show an internal cone 27 which tapers downwardly and has its wall arranged in parallel spaced relation to the wall of the cone 21. The lower end of the cone 27 in Fig. 9 is open at 28 and the cone is supported by a plurality of supporting elements 29 in spaced relation to the wall of the cone 21.

The operation of this device will be obvious. The pipe 18 extends downward to the intake of the carburetor and thus the screen 11 is disposed 45 on the underside of the receiving chamber 10. Under the sucking action of the engine air is drawn in past the screen 11 into the receiving chamber 10, then into the outer end of this receiving chamber just above the chamber 15. It 50 is then drawn downward through the spiral passageway defined by the spiral wall 20 and is discharged into the upper end of the cone 21. It will be noticed that the air is discharged toward the downwardly extending lip 19, so that the air

cannot pass directly upward through the pipe 16, but must pass around the lip before it can enter the pipe 16. This prevents the air with the dust from passing directly up the pipe 16 and permits 5 the dust to settle onto the cone 21 and thus pass downward through the aperture in the bottom of this cone to the dust collecting receptacle 24. If dust collects upon the internal cone 25, the inclination of the wall of this cone will cause the 10 dust to move downward by gravity and pass between the lower edge of cone 25 and cone 21 into the lower end of cone 21 and through the passageway in the lower end of this cone into the receptacle 24. In the structure shown in Fig. 9, dust 15 will pass down from the wall of cone 21 through the space between the interior cone 27 and the wall 21, or it will be discharged onto the interior face of cone 27 and then be discharged into the lower end of cone 21.

20 It will be seen that there are no moving parts in my construction. The dust is separated from the air through centrifugal action and by the partial vacuum caused by the pull of the motor. The dust is deposited in a glass receptacle which 25 is easily detached for cleaning.

30 Air cleaners operating on the general principle of mine have been used for many years, but my improved air cleaner extracts extremely fine dust from the air, even dust as fine as the dust from vegetable matter.

35 It is to be noted that the cone 25 is disposed well down within the cone 21 both in Fig. 8 and Fig. 9. This allows full and free action of the centrifugal force of the air as it passes around cone 21, yet allows the dust to pass between the cone 21 and the interior cone 25 into a quiet or non-turbulent space where the dust can settle freely to the bottom. The lip 19 particularly helps this action as it prevents the force of the 40 air as it leaves the spiral passageway, from agitating the air which is entering the mouth of the central pipe 16. The cone 25 (or cone 27) prevents the force of the air from disturbing the dust that has passed between the outer and inner 45 cones, thus permitting the dust to fall freely into the dust collecting jar. The screen 11 is relatively coarse and is only intended to keep out straw or other large objects. By reason of the fact that this screen or the intake formed there- 50 by is on the lower or bottom side of the casing 10, there is no chance of splashing mud or driving rain striking this intake and fouling the cleaner as is the case where the intake is on the side or top of the receiving chamber.

55 I have illustrated the pipe 18 as extending downward from the casing 10, but I do not wish to be limited to this inasmuch as this pipe 18 might extend in any direction from the duct 17 either upward, downward or laterally.

60 While I have heretofore described this invention as particularly adapted and intended for separating dust and other foreign particles from the air entering a carburetor, it is to be understood that this mechanism might be used in any 65 place where air cleaning is desirable, as, for instance, for suction cleaning devices or for air compressors and other pieces of apparatus.

What is claimed:—

1. An air cleaner for the purpose described, 70 having an air receiving chamber provided with an air opening, a circular chamber into which the receiving chamber opens and having therein a centrally disposed pipe open at its lower end, a spiral wall within the circular chamber defining a spiral downwardly leading passageway be-

tween the wall of the chamber and the central pipe, a downwardly contracted cone forming a downward extension of the circular chamber and having a relatively small discharge opening at its lower end, said pipe extending into and having its lower end below the plane of the top of said cone, a receptacle receiving the material discharged through said cone, a second cone disposed entirely within the first cone and mounted in spaced relation thereto, and an air conducting 10 pipe leading to a carburetor and communicatively connected to the outlet end of the first-named centrally disposed pipe.

2. An air cleaner for the purpose described, having an air receiving chamber provided with 15 a downwardly directed air inlet in its bottom, a circular chamber into which the receiving chamber opens tangentially, the circular chamber extending downward from the receiving chamber, a centrally disposed air outlet pipe extending downward through the circular chamber, a spiral wall defining a downwardly leading spiral passageway between the wall of the circular chamber and said pipe, the pipe at its lower end being below the lower end of the spiral passageway and having 20 a downwardly extending lip on one side and the discharge opening of said passageway being on the same side as said lip, a downwardly tapering hollow cone forming an extension of the circular chamber and having a relatively small discharge 25 opening at its lower end, a receptacle detachably engaged with the lower portion of said cone and into which the cone discharges, a second cone disposed entirely within the first-named cone and mounted in spaced relation thereto, the said pipe 30 having its lower end within said hollow cone and an air conducting pipe leading to a carburetor and communicatively connected to the outlet end of the first-named centrally disposed pipe.

3. An air cleaner for the purpose described, 40 having an air receiving chamber provided with a screen in its bottom, a circular chamber into which the receiving chamber opens and having therein a centrally disposed pipe open at its lower end, means defining a spiral passageway between 45 the wall of the chamber and the central pipe, a downwardly contracted cone extending downward from the circular chamber and having a relatively small discharge opening at its lower end, a receptacle receiving the material discharged 50 through said cone, a second cone disposed entirely within the first cone and mounted in spaced relation thereto, the said central pipe extending below the lower end of said passageway and terminating in said first cone in close proximity to the second 55 cone, and an air conducting pipe leading to the carburetor and communicatively connected to the outlet end of the first-named centrally disposed pipe.

4. An air cleaner, comprising an air receiving 60 receptacle having an air inlet opening in its underside, a cylindrical vertically disposed chamber having an air inlet leading thereinto tangentially from said air receptacle, a downwardly tapering hollow cone extending from and forming 65 a continuation of the lower part of said cylinder, said cone having its apex open for the escape of dust, a pipe disposed co-axially of and within said cylinder and having its lower end extending into said cone and tapering at one side to a downwardly extending lip, means within the cylinder 70 forming a downwardly extending spiral path between the wall of the cylinder and said pipe, said spiral path terminating above the open lower end of the pipe and adjacent the side of the pipe from 75

which the lip extends, a dust collecting receptacle secured to the apex of said cone, a cone supported within the lower part of the first cone and having its periphery in spaced relation with the wall of the latter and having its apex directed upwardly into the open lower end of said pipe, said lip extending downwardly beyond the apex

5 of the second mentioned cone, and an air conducting pipe having communication at one end with the upper end of the first mentioned pipe and adapted to have its other end connected with the air intake of a carburetor.
